EDMUND VARLEY, OF PIETERMARITZBURG, NATAL, SOUTH AFRICA.

BOOK-POSTING DEVICE.

1.304,223.

Specification of Letters Patent. Patented May 20, 1919.

Application filed January 19, 1917. Serial No. 143,253.

To all whom it may concern:

Be it known that I, EDMUND VARLEY, a subject of the King of Great Britain, residing at Pietermaritzburg, Natal, South Africa, have invented a new and Improved Book-Posting Device, of which the following is a full, clear, and exact description.

My invention has for its object to provide a book posting device having two rollers spaced apart, a tough, absorbent paper being rolled on one of the rollers and having an end secured to the other roller so that the said paper may be rolled thereon, the tough absorbent paper being disposed under a plate between the rollers to permit the plate when the device is used to press the tough absorbent paper against a ledger entry, thereby blotting the entry and at the same time recording the entry upon the tough absorbent paper, which permits the book-keeper to add the entries on the tough absorbent paper when removed from the device, thereby ascertaining if the sum agrees with the sum in the primary entry book.

Additional objects of the invention will appear in the following specification, in which the preferred form of the invention is described.

In the drawings similar reference characters denote similar parts in all the views, in which—

Figure 1 is a perspective view illustrating the method by which the device is to be employed;

Fig. 2 is a sectional elevation of the device;

Fig. 3 is a sectional view on the line 3—3 of Fig. 2;

Fig. 4 is a fragmentary view of the tough absorbent paper used with my device; and

Fig. 5 is a rear view of Fig. 4 showing how the fac-simile of the entry may be read at the reverse side of the tough absorbent paper.

By referring to the drawings, it will be seen that the device is constructed with a plate 6, the sides 7 of which are bent up as best illustrated in Fig. 2 of the drawings, there being bearings 8 in the said sides 7 in which spindles 9 and 10 are journaled. There are two bearings 8, at each side 7, and two sets of spindles 9 and 10, so that a roller 11 may be mounted on one set of spindles 9 and 10, a roller 12 being mounted on the other set of spindles 9 and 10. The rollers

11 and 12 are engaged by flanges 22 on the spindles 9 and keys 21 on the spindles 10.

Mounted on each of the spindles 9 there is a spring 13 which presses at one end against a bearing 8 and at the other end against a flange 22 on the spindle, this means being provided for holding the rollers in position under slight pressure so that they will be engaged by the keys 21 on the spindles 10. The teeth on the peripheries of the wheels 14 mounted on the spindles 10 engage the terminals of a spring 16, this spring being secured by a screw 17 to a seat 18 projecting upwardly from the plate 6. Each of the spindles 10 is prolonged and is provided with a finger piece 19 by which it may be readily rotated.

A strip of tough absorbent paper 20 is rolled on one of the rollers 11 or 12, and the end of this strip of tough absorbent paper is secured to the other roller 11 or 12, so that when the roller to which the said end is secured is rotated the strip of tough absorbent paper which passes under the plate 6 will be moved relatively thereto.

The device is intended to be used when copying entries from a primary entry book in a ledger, the entry in the ledger being blotted by pressing the tough absorbent paper at the plate 6 down against the entry, a fac-simile of the entry being produced on the tough absorbent paper at the same time. After blotting each entry, the roller 11 or 12 to which the end of the tough absorbent paper is secured, is rotated by its thumb piece 19 so that a new surface of the tough absorbent paper 20 will be disposed under the plate 6 to be used to blot the next entry and receive a fac-simile thereof. At any time the bookkeeper may ascertain whether the amounts of the entries in the ledger are correct by adding up the figures in the primary entry book, and adding the figures on the reverse side of the tough absorbent paper.

If the sums agree the bookkeeper may be certain that no error has been made in making the entries in the ledger.

Should any of the impressions on the tough absorbent paper be faint, so that it is difficult to read them through the paper, oil or some other substance which will render the paper transparent may be applied to the paper, which will permit the bookkeeper to readily read the entries on the reverse side.

To avoid errors, such as posting debits

on the credit side of the ledger and vice versa, ink of a different color may be employed for all credit entries, or, if desired, the distance between the date and the money 5 column may be greater or less on the credit side of the ledger than on the debit side, this having the effect of throwing the impressions of the entries posted on the credit side out of alinement with those posted on the 10 debit side of the ledger.

Having thus described my invention, I claim as new, and desire to secure by Letters Patent:

1. In a book posting device, a member 15 having substantially parallel sides with bearings, spindles disposed in the bearings, two rollers having openings in their ends in which the ends of the spindles are disposed, means on the spindles at one side of the 20 member to prevent the rotation of the rollers relatively to the spindles, wheels with teeth mounted on the last mentioned spindles, a spring secured to the member and having terminals engaging the teeth, resilient means 25 for holding the spindles at one side of the

member in the direction of the spindles at the other side of the member, and a tough absorbent paper wound on one spindle and secured to the other spindle.

2. In a book posting device, a bottom 30 member having substantially parallel sides with bearings, spindles journaled in the bearings, two rollers having openings in their ends in which the spindles are disposed, means on the spindles at one side of 35 the member to prevent the rotation of the rollers relatively to the spindles, wheels with teeth mounted on the last mentioned spindles, a spring secured to the bottom member and having terminals engaging the teeth, resilient means for holding the spindles at one side of the member in the direction of the spindles at the other side of the member, and a tough absorbent paper wound on one of the rollers disposed under the bottom member and secured to the other roller, the tough absorbent member being exhibited at the rollers at all times.

EDMUND VARLEY.
